UNITED STATES PATENT OFFICE.

DANIEL H. TAYLOR, OF PALISADES, COLORADO.

DEVICE FOR PREVENTING COLLISIONS AT SEA.

1,020,330.

Specification of Letters Patent. Patented Mar. 12, 1912.

Application filed June 3, 1910. Serial No. 564,901.

To all whom it may concern:

Be it known that I, DANIEL H. TAYLOR, a citizen of the United States, residing at Palisades, in the county of Mesa and State of Colorado, have invented new and useful Improvements in Devices for Preventing Collisions at Sea, of which the following is a specification.

This invention relates to devices for preventing collisions of ships at sea with other ships, icebergs and also from grounding.

The object of the invention is the provision of a device of this character which when contacted by a ship, iceberg, ground or rocks will sound an alarm in sufficient time to permit the engine of the ship to be reversed and saved from contact with the object even when the vessel is traveling at its highest rate of speed.

Further objects of the invention will appear as the following specific description is read in connection with the accompanying drawings which form a part of this specification, and in which:

Figure 1 is a side elevation of a vessel showing my improved collision protector attached thereto. Fig. 2 is a top plan view. Fig. 3 is a detail horizontal section on the line 3-3 of Fig. 1. Fig. 4 is a similar section on the line 4-4 of Fig. 1. Fig. 5 is a detail section of the ground ball.

Referring more particularly to the drawings 1 represents the ship to the bow of which is connected the flexible cords 2 and 3 which have connected to their outer ends the motor frames 4 and 5 in which are positioned suitable electric motors 6 and 7 having connected to their driving shafts the propellers 8. These motors are supported and held submerged a slight distance from the surface by floats 9 which are connected to the motor frames by flexible links 10. The motors 6 and 7 are arranged on opposite sides of the vessel and the propellers have their blades so constructed that when the motors are driven the frames and their associated parts are kept away from the sides of the vessel as shown in Fig. 2 and with the cords or connecting devices 2 and 3 held taut. A similar motor frame 11 having a motor 12 and propeller 13 is connected to the motor frames 4 and 5 by means of flexible conduits 14 in which the circuit wires

15 of suitable alarm systems are connected. This motor 12 is also provided with a float 16 so as to hold it suspended slightly below the surface of the water and has a flexible conduit 14 extending entirely around the front of the frame.

In the practical use of the device the circuit wires 15 for the alarm systems and for the motors will pass downwardly from the rail 17 of the vessel through a protecting tube 18 which is provided with a pulley 19 at its lower end to permit a frictionless passage of the wire cable 15 to the motors and conduits 14. The circuits may be divided into separate sections, one adapted for the conduit on the left hand side, the other adapted for the conduit on the right hand side and the third adapted for the conduit at the head frame 11 and the other for the motors and these wires may be connected together in a single cable, which passes through the tube 18 and over the pulley 19. These separate sections of the alarm circuit may have separate bells or may all control a single alarm, but I prefer the former as it will then indicate upon which side the contact is made or whether it is made at the head.

Carried by the conduits 14 at intervals throughout their lengths are suitable contact springs 20 which have secured thereto the contact buttons 21 projecting through the sides of the conduit and adapted to be engaged by a ship, iceberg or the like and to operate the springs 20 to bring them into engagement with the contact points 22. The spring 20 is connected by way of a lead 23 to one of the circuit wires 14 and the contact 22 is connected by way of a lead 25 to the opposite circuit wire 26. This parallel arrangement is common and needs no further description, it being understood that all of the contact buttons 21 are connected in the same manner and when the separate circuits are used for different alarms the circuit on one side is identical with the circuit on the opposite side, but disconnected therefrom as is also the circuit of the head contact. In order to separate these sections, I might indicate them by the reference letters, a-b indicating the left hand section, b-c the head section and c-d the right hand section. The motor connecting cords 2 and

3 may be connected in any suitable manner to the ship so that they may be lengthened or shortened as is found desirable and the cable 15 may be mounted upon a windlass 5 so that it can be let out or taken in to increase or decrease the distance between the alarm contacts and the ship.

Depending from the frames 4, 5 and 11 and connected thereto by the circuit wires 10 27 which also pass through the conduits 14 and are connected in the cable 15, are contact balls 28 which have the contact buttons 29 projected from their circuits and adapted to operate the circuit closers in the manner 15 described for the circuit closers carried by the conduits 14. The circuits for these devices are preferably in series and the circuit on the ball which depends from the frame 11 is separated and distinct from its mates, 20 so that it may be immediately ascertained where such contact is made. These balls are arranged so that they hang in the water a short distance below the keel of the vessel as shown in Fig. 1.

Having thus described the invention, 25 what is claimed is—

A protector for ships comprising a flexible conduit, alarm circuit wires carried therein, circuit closers connected to said wires and carried by the conduit, frames 30 connected to the conduit, a propelling device carried by one of the frames and adapted to drive the conduit in a direction of the progress of the ship, propelling devices carried by the other frames and adapted to 35 drive the ends of the conduit in a direction laterally of the progress of said ship, circuit closing devices depending from the frames, and flexible members adjustably connecting the lateral propelling devices 40 with the ship.

In testimony whereof I affix my signature in presence of two witnesses.

DANIEL H. TAYLOR.
